DESIGN FOR A RECORDER FRAME

Richard G. Leitner and William K. Rieber, West Los Angeles, Calif., assignors to Frank Rieber, Inc., West Los Angeles, Calif., a corporation of California

Application March 29, 1943, Serial No. 109,851

Term of patent 7 years

To all whom it may concern:

Be it known that we, Richard G. Leitner and William K. Rieber, citizens of the United States of America, residing in West Los Angeles, in the county of Los Angeles, State of California, have invented a new, original, and ornamental Design for a Recorder Frame, of which the following is a specification, reference being had to the accompanying drawing, forming a part thereof.

Fig. 1 is a perspective view of a recorder frame showing my new design as viewed from the top, front and one side thereof;

Fig. 2 is a top plan view of said recorder frame;
Fig. 3 is a bottom plan view of the same;
Fig. 4 is a front elevational view of the same;
and

Fig. 5 is a side elevational view of the same.
We claim:

The ornamental design for a recorder frame, as shown.

RICHARD G. LEITNER.
WILLIAM K. RIEBER.
